ELECTRON TUBE FOR THE OPTICAL INDICATION OF AN ELECTRICAL MAGNITUDE

Gerrit Hendrik Petrus Alma, Willem Keeman, Carel Peter Kloppen, and Dirk Cornelis Kraanen, all of Eindhoven, Netherlands, assignors to North American Philips Company, Inc., New York, N.Y., a corporation of Delaware

Filed Oct. 3, 1958, Ser. No. 765,194

Claims priority, application Netherlands Oct. 4, 1957

1 Claim. (Cl. 313—92)

The invention relates to electron tubes for the optical indication of the occurrence of an electrical magnitude such as a load, current or voltage, more particularly on a tube which may be operated at voltages lower than 100 volts and which is suitable for use in computers and counters and the like, possibly in co-operation with transistors.

In such devices, which usually operate by the binary system, in most cases electric discharge tube indicators are used to indicate the 0- or the 1-condition.

However, in transistor circuits, the voltages applied are usually too low to obtain satisfactory indication, so that it was necessary to utilize separate, higher supply voltages for these indicators.

It has been found that a distinct and reliable indication can be obtained at supply voltages below 100 volts by means of an electron tube containing a cathode, one or more grids and an anode covered with luminescent material if, according to the invention, the anode comprises a grid, the wires of which are covered with luminescent material at least for part of the surface remote from the cathode. The grid which serves as an anode is preferably arranged wholly at one side of the cathode, it being possible for a reflector electrode to be arranged at the opposite side of the cathode. In one determined embodiment, the wires of the anode are located in one plane. The pitch of the wires is preferably chosen to be comparatively high with respect to that of the control grid. On the one hand, the wires are required to be spaced to an extent such that electrons in sufficient quantity can pass between them and, on the other hand, it is desirable for them to be spaced so closely that, as seen from some distance, the luminous parts of the wires seem to produce a luminous column along the longitudinal axis of the tube.

In order that the invention may be readily carried into effect, several embodiments will now be described in detail, by way of example, with reference to the accompanying drawing.

In Fig. 1, reference numeral 1 indicates the bulb of a high-vacuum tube containing a filamentary cathode 2, which is surrounded by a control grid 3. A reflector elec-

2

trode 4 is arranged at one side of the cathode 2, an anode 5 arranged at the opposite side of cathode 2 comprising an elliptic grid of high pitch, of which at least the parts of the wires most adjacent the cathode are covered, on the side opposite the cathode, with luminescent material 6, such as willemite. As a rule, luminescent material is sprayed onto the whole grid.

It has been found that electrons can penetrate from the cathode into the space enclosed by the anode 5, but substantially return as a result of space charge in this space and arrive at the luminescent surface of the parts of the wires most adjacent the cathode. Luminescent points are then produced on the various wires, which provides a clear indication. If the control grid 3 becomes sufficiently negative, the luminous points disappear. The tube may thus provide an indication as to whether, for example, a circuit connected to the control electrode 3 conveys current or a given point has a positive or negative potential with respect to the cathode 2. The electrode 4 is connected to a low potential, for example to the negative terminal of cathode 2.

It appears that clear luminescence already occurs at an anode voltage of from 25 to 50 volts, which voltage is usually already available in computers. Furthermore, the anode current is found to be completely suppressed at a negative voltage of a few volts on control grid 3, so that this electrode may be connected, if desired, to the collector of a transistor.

In the embodiment shown in Fig. 2, the anode has the shape of a half-grid 7, which may be obtained by pressing the wires of a wound grid into one plane. In Fig. 3, the anode is constituted by a flat grid 8.

Fig. 4 is a view of a tube as shown in Figures 1, 2 or 3, in which in the event of the tube conveying anode current, a series of small luminous lines 9 may be seen, produced by the luminous parts of the wires of the anode.

What is claimed is:

An electron discharge tube for the optical indication of an electrical magnitude adapted to operate at voltages lower than 100 volts comprising a cathode having a given axis, a control electrode, a reflector electrode located on one side of the cathode, and an anode comprising an elliptical grid located wholly on the other side of the cathode, said anode further comprising only a plurality of spaced substantially parallel wires which are perpendicular to the axis of the cathode and covered at least on their surface portions remote from the cathode with a luminescent material, said wires being spaced apart a distance at which electrons readily pass between the wires while the wires when struck by electrons produce a luminous column along the longitudinal axis of the tube.
